[57] CLAIM

The ornamental design for the finger ring, as shown and described.

DESCRIPTION

FIG. 1 is a perspective view of a finger ring showing my new design;

FIG. 2 is a front elevational view, the opposite side view being the same;

FIG. 3 is a side elevational view, the opposite side view being the same;

FIG. 4 is a top plan view;

FIG. 5 is a bottom plan view;

FIG. 6 is a side elevational view shown in an alternative position;

FIG. 7 is a front elevational view of FIG. 6;

FIG. 8 is a top perspective view of a finger ring showing a second embodiment of my new design; and,

FIG. 9 is a top plan view of FIG. 8.

The broken line showing of gemstones in FIGS. 8 and 9 are for illustrative purposes only and form no part of the claimed design.
